UNITED STATES PATENT OFFICE.

PATRICK GATELY, OF NEW YORK, N. Y.

SAFETY ATTACHMENT FOR ELEVATORS.

SPECIFICATION forming part of Letters Patent No. 243,771, dated July 5, 1881.

Application filed May 19, 1881. (No model.)

To all whom it may concern:

Be it known that I, PATRICK GATELY, a citizen of the United States, residing at New York, in the county and State of New York, 5 have invented a new and useful Safety Attachment for Elevators, of which the following is a specification, reference being had to the accompanying drawings.

My invention relates to an attachment for 10 an elevator which has a pulley or drum on which the hoisting-rope winds; and it consists in a frame or receiver so located with reference to said drum, and so connected to and operating with the valve and other mechanism, as 15 hereinafter described, that should the said rope break or become loose on the drum the loosened rope, by falling on said frame or receiver, shall be the means of stopping the motive engine.

20 In the drawings, Figure 1 is a side elevation of so much of a device embodying my invention as serves for illustration. Fig. 2 is a plan, and Fig. 3 a front elevation, of the same.

The drum or pulley A, on which winds the 25 hoisting-rope a, is on the shaft b, and is located in the machine in the ordinary manner.

Under the drum A, in suitable relation thereto, is the frame or receiver B, which is of 30 sufficient size and of construction proper to receive any part of the rope a which may drop or sag down from close contact with the drum. The frame B is so hung as to form part of a lever, or be attached to a lever, C, pivoted as by the bar or shaft c, having places of bearing d d in fixed supports. There is an arm, 35 e, of the lever C, which is weighted or is of sufficient weight to keep the lever in the position shown when there is no extra weight on the frame B. There is another arm, f, of the 40 lever C, to which is pivoted a rod, D. The other end of this rod rests on a fixed pin or stop, g. There is another lever, E, having a weight, h, and pivoted at i to a fixed support.

One arm, j, of the lever E is to move part 45 of a clutch, F; and the other arm, k, rests on the rod D when the part l of the clutch is out of engagement with the other part, m. The clutch F is on a shaft, G, which is to revolve in suitable fixed bearings, the part m being fixed to the shaft, and the part l being 50 loose on the shaft and having fixed to it a gear,

H. In proper relation to the gear H to engage therewith is a segment, I, of a gear, which is pivoted at n to fixed supports.

On the segment I is a stud or pin, o, on 55 which is pivoted one end of a rod, J. The other end of this rod is pivoted to a lever, K, at p. One end of the lever K is pivoted to a fixed support at q.

The pipe L may represent the exhaust-pipe 60 of the engine, or the supply-pipe, or the valve-chest. It contains a valve for closing the passage in box M, having the valve-stem r. A lever, N, having a weight, s, is pivoted at one end, t, to a fixed support, and rests at the 65 other end on the lever K, as shown, when the valve in box M is open.

The mechanism being substantially as described, and the parts in position, as shown in the drawings, when the rope a breaks or becomes loose on the drum, as the result of the elevator-car getting caught, or from other causes, it will drop or sag onto the frame B, moving the same downward and swinging the lever C. The end of the rod D will therefore 70 be pulled from under the lever E, which will swing, being moved by the weight h, and bring the part l of the clutch into engagement with the part m, so that the gear H will be revolved by the shaft G, this shaft being in constant 75 revolution while the engine is in operation. The segment I, being in engagement with the gear, will be swung, and hence the lever K will be pulled from under the lever N by means of the rod J. The lever N will therefore 80 upon be swung downward by the weight s, and hence the valve be moved by means of the stem r, and the passage of steam or water stopped, and the engine will cease to act. Further disarrangement of the hoisting-rope, 85 and any accident that might result from the continued motion of the engine and machine, including the revolving of the drum A, while the free movement of the car is obstructed, will thus be prevented. Before the engine and 90 machine are again put in action the engineer or other person in charge will put the mechanism described in condition for action, as specified.

I claim as my invention--

1. In an elevator, a frame or receiver set in relation to the drum on which winds the hoist-

ing-rope, and operated by the loosened rope, substantially as and for the purpose set forth.

2. The combination of the drum A, frame B, lever C, and rod D, substantially as described.

3. The combination of the shaft G, having thereon the clutch F and gear H, with the segment I, lever E, rod D, and mechanism for operating rod D by the hoisting-rope, substantially as specified.

4. The combination of the lever N, to operate the valve, with the lever K, rod J, and mechanism for moving rod J by the hoisting-rope, substantially as specified.

15 5. In an elevator, a valve for closing the

supply or exhaust passage of the motive engine, operated by the hoisting-rope when it drops from or becomes loose on the drum, substantially as set forth.

6. An elevator mechanism, substantially as described, whereby the hoisting-rope, when it falls from or becomes loose on the drum, connects, for moving a valve, a part of the machinery, as the shaft G, having continued motion.

PATRICK GATELY.
